UNITED STATES PATENT OFFICE.

WALTER W. MACFARREN, OF PITTSBURGH, PENNSYLVANIA.

COOLING MEANS FOR GAS-ENGINE CYLINDERS.

1,161,493.

Specification of Letters Patent. Patented Nov. 23, 1915.

Application filed July 30, 1913. Serial No. 782,037.

To all whom it may concern:

Be it known that I, WALTER W. MACFARREN, a citizen of the United States, residing at Pittsburgh, in the county of Allegheny, State of Pennsylvania, have invented certain new and useful Improvements in Cooling Means for Gas-Engine Cylinders, of which the following is a specification.

My invention relates to means for cooling gas engine cylinders and is particularly adapted for automobile engines.

The objects of my invention are: 1. To provide efficient cooling means integral with the engine and thus to dispense with a radiator and piping. 2. To provide means whereby a free and rapid circulation of the cooling water is effected by heat alone thus dispensing with a pump. 3. To reduce the weight of cooling water and of the apparatus itself. 4. To cool the water in the jacket by means of the surrounding air and to use a metal for the jacket such as copper having a high conductivity for heat. 5. To divide the jacket water into two portions one of which is receiving heat from the cylinder and the other of which is delivering heat to the jacket. 6. To increase the radiating effect of the jacket by corrugation and to further increase it by exterior fins. 7. To provide means for indicating an excessive temperature in the jacket.

Referring to the drawings Figure 1 is a diagrammatic sectional plan of a 4 cylinder engine equipped with my invention. Fig. 2 is a vertical section through one cylinder thereof and Figs. 3-4 and 5 are detail views of different forms of corrugations for the jacket.

As this invention is applicable to either two or four cycle engines with various arrangement of valves and shapes of cylinders, no valves have been shown in the drawings it being understood that it is well within the skill of the designer to adapt my invention to the details of the cylinder to be cooled.

The cylinders 1 may be cast "en bloc" as shown or in any desired manner. The sheet metal jacket 2 may inclose all the cylinders as shown or a separate jacket may be provided for each cylinder. The jacket 2 is preferably made of thin sheet copper bent or corrugated in any one of various forms which may suggest themselves, certain suitable forms of corrugations being indicated in Figs. 3, 4 and 5. The object of the cor-

rugations being to split up the water into thin streams and to increase the exterior surface of the jacket they should be deep and closely spaced. To still further increase the conduction and radiation of heat from the jacket I provide serrated projecting ribs or "fins" which may be either integral with the jacket or attached thereto as by riveting or soldering. While both the corrugations 3 and fins 6 may be horizontal or inclined, it is preferable to make them vertical, thus being parallel to the flow of both water and air currents.

Referring to Fig. 2 the jacket 2 extends from top to bottom of the cylinder or as far up and down as convenient, according to the design of cylinder. The jacket 2 is provided with a tight cover 7 and a filler cap 8. A small "indicator" pipe 9 may be led, to the dash to indicate boiling of the water by the escape of the steam. A baffle plate 10 extends vertically from near the bottom of the jacket to near the top of the same and surrounds the cylinder or cylinders leaving a space above and below for the passage of the water from one side of the plate 10 to the other. The plate 10 is fastened to small lugs 11 on the cylinders. In action the heated water in the space 12 between the cylinder walls and the baffle plate 10 rises and passes over the upper edge of the plate to the space 13 between the plate 10 and the jacket 3. The space 13 communicates with the numerous small spaces 14 inclosed by the corrugations 3 and the water is thus subdivided into thin streams which are quickly cooled.

By the above arrangement a continuous rapid unimpeded circulation is maintained in the jacket 3 as long as there is any heat generated in the cylinder.

It will be understood that the jacket 3 is to be designed to suit the size and temperature of the cylinders to be cooled and it will be seen that that with proper design the jacket can be made so the engine can never overheat even in warm climates and this can be tested experimentally by running the engine under full load in a closed box the air in which is maintained at the maximum temperature of the climate.

It will be apparent that instead of using corrugations in the jacket for subdividing the downwardly moving stream of water the same effect could be obtained by using

a number of small tubes of round, square or flat section but this would merely increase the cost of manufacture without adding materially to the efficiency of the apparatus.

- 5 From the above it will be seen that I have provided a simple and efficient apparatus for cooling gas engine cylinders which dispenses with the radiator, piping and pump usually employed on automobile engines and have retained all the well known advantages of water cooling with nearly as simple apparatus as usually employed for air cooling. The invention combines the merits of these two systems with the usual defects of

15 neither.

I claim as my invention—

1. A gas engine cylinder and cooling means therefor, comprising a water jacket surrounding the cylinder, and provided 20 with exterior vertical corrugations, and a partition within the jacket lying between the exterior of the cylinder and the inner surfaces of the corrugations, said partition having a length less than the length of the 25 jacket leaving a passage way at each end thereof whereby the heated inner space next to the cylinder produces an ascending current, and the surface of the corrugations cool the same and cause it to descend thus 30 maintaining a constant circulation in the jacket to cool the cylinder.

2. A gas engine cylinder and cooling means therefor, comprising a water jacket surrounding the cylinder, and provided 35 with exterior vertical corrugations, and a partition within the jacket lying between the exterior of the cylinder and the inner surfaces of the corrugations, said partition having a length less than the length of the 40 jacket, and spaced from the upper and lower surfaces of the jacket forming communicating water spaces, and the contour of said partition on a section parallel to the cylinder and at a right angle to the shaft being 45 curved to substantial parallelism with the exterior of the cylinder.

3. A gas engine cylinder and cooling means therefor, comprising a water jacket

surrounding the cylinder, an inner space in said jacket through which the water flows 50 upwardly, and an outer space in said jacket through which the water flows downwardly, said outer space being subdivided so the water is subdivided into a number of thin streams, and a vertical partition between the 55 inner and outer spaces and within the jacket, and spaced from the upper and lower surfaces of the jacket forming communicating water spaces.

4. Cooling means for gas engine cylinder, 60 comprising a water jacket provided with vertical corrugations, vertical fins on the outside of some of the said corrugations and a vertical partition within the jacket dividing the same into inner and outer 65 spaces, and spaced from the upper and lower surfaces of the jacket forming communicating water surfaces.

5. A gas engine cylinder and cooling means therefor, comprising a corrugated 70 sheet metal jacket, a flange on the cylinder below the jacket, a cap above the jacket the same being secured to the cylinder and a partition within the jacket separating the water space into inner and outer portions, 75 and spaced from the upper and lower surfaces of the jacket forming communicating water spaces.

6. A plurality of gas engine cylinders and cooling means therefor, comprising a water 80 jacket inclosing more than one of the cylinders and provided with vertical corrugations, and a partition within the jacket parallel to the contour of the jacket and of a less length whereby the water spaced is divided into inner and outer portions and a thorough circulation of the water is induced, 85 said partition being spaced from the upper and lower surfaces of the jacket forming communicating water spaces. 90

In testimony whereof I hereunto affix my signature in the presence of two witnesses.

WALTER W. MACFARREN.
